CLAIM

The ornamental design for a conduit pedestal, as shown and described.

DESCRIPTION

FIG. 1: is a front-left-top perspective view of a conduit pedestal showing my new design;

FIG. 2: is a front elevational view thereof; a rear elevational view being a mirror image;

FIG. 3: is a left side elevational view thereof; a right side elevational view being a mirror image;

FIG. 4: is a top plane view thereof;

FIG. 5: is a bottom plane view thereof; and,

FIG. 6: is a perspective view thereof; with a shaft plant shown in broken lines for illustrative purpose only and forms no part of the claim.
